Patented Feb. 23, 1971

220,013

WARNING SIGNAL

Martin Kaltman, Flushing, N.Y., assignor to Queens Devices, Incorporated, Long Island City, N.Y., a corporation of New York

Filed Apr. 30, 1969, Ser. No. 16,960

Term of patent 14 years

Int. Cl. D29—99

U.S. Cl. D72—1

FIG. 1.

Des. 220,013

PAGE 2

FIG. 2.

FIG. 3.

FIG. 4.

FIG. 1 is a front view of a warning signal showing my new design; and

FIG. 2 is a rear view thereof.

FIG. 3 is an elevational view thereof as taken from the left side of FIG. 1;

FIG. 4 is an elevational view thereof as taken from the right side of FIG. 1.

I claim:

The ornamental design for a warning signal, substantially as shown.
